UNITED STATES PATENT OFFICE.

GEORGE D. GILBERT, OF CORRY, ASSIGNOR TO R. S. BATTLES, OF GIRARD, PENNSYLVANIA.

STEAM-ENGINE.

SPECIFICATION forming part of Letters Patent No. 348,458, dated August 31, 1886.

Application filed May 4, 1886. Serial No. 201,097. (No model.)

To all whom it may concern:

Be it known that I, GEORGE D. GILBERT, a citizen of the United States, residing at Corry, in the county of Erie and State of Pennsylvania, have invented certain new and useful Improvements in Steam-Engines; and I do hereby declare the following to be a full, clear, and exact description of the invention, such as will enable others skilled in the art to 5 which it appertains to make and use the same.

This invention relates to duplex steam-engines; and it consists in certain improvements in the construction thereof, as will be herein-after fully set forth, and pointed out in the 15 claims.

The invention is illustrated in the accompanying drawings, as follows:

Figure 1 is a vertical section taken on the line of the main shaft. Fig. 2 is a vertical section 20 taken on the line $x x$ in Fig. 1, with the valve V omitted.

A A' are the cylinders, which are cast, together with part of the frame, in a manner common to this class of engines.

25 B is a casting, which forms the cap or cover to both cylinders, and has formed within it the live-steam passage S, part of the valve-chamber E, with the valve-seats e, and the steam passages or ports P and P'. The valve 30 V is a double-faced hollow telescoping balanced slide-valve. The live steam enters the valve and passes from it to the ports, and the exhaust-steam enters the valve-chamber. Such valves are of common construction.

35 Between the cylinders A and A', near their top, is a partition-wall, E², which forms the lower end of the valve-chamber, and the exhaust-nozzle E' leads from this part of the chamber.

40 The ports or passages P and P' lead from each valve-seat to their respective cylinders, as follows: The port or passage P leads from the lower ends of the valve-seats to the cylinder A, and the port or passage P' from the upper ends of the valve-seats to the cylinder A'. The cap B has a cover, B', on the side over the valve-chamber, and there is a cover, A², on the side over the space between the two cylinders, which covers, also, that part 45 of the valve-chamber which is below the cap and within the space between the cylinders above the partition E². The valve-stem V'

passes through the partition E², and is guided in an arm, H, which extends out from the cylinder A', near its lower end in the space between the two cylinders. The eccentric-rod V² connects with the valve-stem through the means of a pivot-pin, v, which is clamped to the valve-stem, and, of course, by this means the adjustment of the valve is made. It will 55 be observed that the live-steam passage S in the cap B lies parallel with the shaft G, and that the supply-pipe, when attached to the live-steam passage, will be directly over the shaft. 60

What I claim as new is—

1. In a duplex steam-engine, the combination, with the cylinders, of the cap B, covering both cylinders and having therein the live-steam passage S, part of the valve-chamber E, the valve-seats e, and the ports P P', leading from the opposite ends of the valve-chamber to the cylinders A and A', respectively. 70

2. In a duplex steam-engine, the cylinders A A', the cap B, covering said cylinders and having the steam-passage S, part of the valve-chamber E, with opposite vertical valve-seats e e, and the ports P P', leading from opposite ends of the valve-seats to the said cylinders 80 A and A', respectively, in combination with the double-faced telescoping balanced slide-valve V.

3. In a duplex steam-engine, the cylinders A and A', having part of the valve-chamber 85 formed between them, in combination with a cap covering said cylinders, having the other part of the valve-chamber and the proper steam-passages formed therein, substantially as set forth. 90

4. In a duplex steam-engine, the cylinders A and A', having part of the valve-chamber and the valve-stem guides formed between them, and a cap or cover having the other part of the valve-chamber and the proper 95 steam-passages formed therein, substantially as set forth.

In testimony whereof I affix my signature in presence of two witnesses.

GEO. D. GILBERT.
